UNITED STATES PATENT OFFICE.

DON CARLOS TRAVIS, OF KENOSHA, WISCONSIN, ASSIGNOR TO SIMMONS COMPANY, OF KENOSHA, WISCONSIN, A CORPORATION OF DELAWARE.

SHIP-BUNK.

1,284,821.

Specification of Letters Patent. Patented Nov. 12, 1918.

Application filed February 25, 1918. Serial No. 219,079.

To all whom it may concern:

Be it known that I, DON CARLOS TRAVIS, a citizen of the United States, residing in the city of Kenosha, county of Kenosha, and State of Wisconsin, have invented certain new and useful Improvements in Ship-Bunks, of which the following is a specification.

My invention relates to improvements in ship bunks and has for its objects to provide a removable bunk which may be folded or collapsed into very small compass when not being used; to provide a bunk of the class described which may conveniently 10 swing from horizontal into perpendicular position thereby to provide more space beneath the bunk; to provide a construction which shall be simple in design and economical to manufacture and in general to provide 15 an improved ship bunk of the character referred to.

In the drawings which illustrate a preferred embodiment of my invention—

Figure 1 is an end elevation of an upper 20 and lower bunk made according to my invention.

Fig. 2 is a fragmentary elevation looking in the direction of the arrows 2—2 in Fig. 1.

Fig. 3 is a fragmentary elevation looking 25 in the direction of the arrows 3—3 of Fig. 1.

Fig. 4 is a fragmentary enlargement of a portion of Fig. 1.

Fig. 5 is a plan view of one of the bunks showing the parts in the position occupied 30 after the bunk has been removed from its supports and folded flat.

Fig. 6 is an end elevation of the bunk shown in Fig. 5.

Fig. 7 is a side elevation of the ends of 35 the lower bunk shown in Fig. 1.

Referring to the drawings, it will be seen that the upper bunk 10 and the lower bunk 11 are detachably supported upon a pair of rear stanchions 12 and 13 and a pair of front 40 stanchions 14 and 15, said stanchions comprising lengths of heavy steel or iron tubing, the ends of which are suitably secured to the floor and roof of the deck of the vessel, for instance by means of sockets 16. In some 45 instances, of course, it may be unnecessary to provide a full set of stanchions for each pair of bunks there being many cases in which it may be possible or desirable to use the bulk heads or side walls of the ship's

hull, in place of the independent stanchions 55 just mentioned.

In the preferred form of my invention each bunk is equipped with a resilient bed bottom which, in the present instance, comprises a wire link fabric 17 resiliently 60 stretched or supported in the bunk frame by means of helicals 18. Preferably an independent transverse row of the said helicals 18 is provided at each end of the bed fabric 17, the outer ends of the said helicals being 65 hooked in the apertures 19 punched in the horizontal web of an angle iron 20, the said angle irons 20 constituting the end bars of the frame which inclose the bed bottom. The side members of the bed bottom frame 70 comprise a pair of parallel spaced apart steel or iron tubes 21 which connect the outer ends of the angle bars 20 and in order to form an efficient connection, the ends of the said angle bars 20 are equipped with small 75 socket members 22. The said socket members 22 are furnished with lugs 23 which are united to the horizontal webs of the angle bars 20 by means of rivets as shown at 24 and the outer ends of the said socket members 22 are apertured to slidably receive the 80 extremities of the side tubes 21. Preferably the sockets 22 are prevented from sliding toward each other along the side tubes 21 by reason of the vertical web 25 of the end bar 85 constituting a stop or abutment at the outer ends of the apertures in the said sockets. In order to prevent the fabric from sagging unduly from the weight of the occupant, the bunk is equipped with one or more flexible 90 slat members 26, the ends of which are connected to clamps 27 surrounding the side tubes 21 by means of helicals 28.

The bunk is hung or supported between the stanchions 12, 13, 14 and 15 by means of 95 devices associated with the ends of the lee rails 29 and 30, said lee rails 29 and 30 being hinged or pivoted to the side tubes 21 by means of a series of arms or rods 31, the ends of which are riveted into the said lee rails 29 and 30. In order to provide the necessary pivotal connections between the rods 31 and the side tubes 21, the latter are made circular as shown and the rods 31 are equipped at their ends with eyes 32 which 100 loosely embrace or inclose the said side tubes 21.

In order to maintain the lee rails 29 and

30 at the desired distance apart when the bunk is in effective use, I employ a pair of spacer tubes 33, the ends of which are open and adapted to receive the heads of short 5 studs 34 riveted into the ends of the lee rails 29 and 30. The ends of the studs 34 are, of course, suitably pointed so that they will readily enter the open ends of the spacer tubes 33. The spacer tubes 33 are also pivotally connected to the frame of the bunk, 10 this being accomplished by virtue of pairs of rods 35, the outer ends of which are riveted or otherwise secured into holes in the spacer tubes 33, the pivotal connection being 15 effected by means of small angle brackets 36 riveted through the vertical web of the angle bars 20. The pivot pins 37 form the hinge connection between the lugs of the brackets 36 and the flattened perforated ends 20 of the rods 35.

By means of the construction just described it will be manifest that the bunk may be collapsed as shown in Fig. 5 or 6 or it may be adjusted into the set-up or operative position as illustrated in Fig. 1. The means for supporting the bunk in the stanchions 12, 13, 14 and 15 comprise a set of stamped metal sockets 38, the outer ends of which are forked as shown at 39 in order 25 to inclose the stanchions, rigid connection between the sockets 38 and the stanchions being effected by means of rivets 40 which pass through the stanchions and forked ends 39. The sockets 38 take the form of hollow 30 cylinders the axes of which are horizontal, the upper surface of the said cylinders being cut away as shown best in Fig. 4 to admit the ends of the lee rails 29 and 30. The internal diameter of the sockets 38 is considerably greater than the external diameter 35 of the lee rails which are accurately located concentric with the sockets by providing the sockets 38 with integral end flanges 41 vertically slotted as shown at 42 to receive the 40 ends of the lee rails and accurately position the same.

The ends of the lee rails are prevented from moving axially out of the sockets 38 by means of transverse studs or pins 43 extending diametrically through the ends of the lee rails and having projecting portions 44 substantially as long as the depth of the flanges 41. It is to be observed by reason of the aforesaid projecting portions 44 the ends 45 of the lee rails are positively locked within the sockets 38 and cannot be accidentally displaced therefrom due to any springing apart or other movement of the stanchions 12, 13, 14 and 15. It will be observed also that 50 the said pins 43 do not interfere with the swinging of the bunk into a vertical position as shown in full lines in the upper part of Fig. 1, while at the same time when the bunk is swung into vertical position, the 55 pins 43 assume a horizontal position and

thus positively prevent the ends of the lee rails from jumping out of the tops of the sockets 38.

When the upper bunk is moved into the full line position shown in Fig. 1, it is prevented from dropping back into horizontal position by means of a pair of locking devices one of which is shown in Fig. 2. Said locking device comprises a small stamping 70 preferably of inverted channel shape in cross-section, the vertical lugs 46 being spaced apart a sufficient distance to inclose the stanchions. Except as to its outer end 47, the said stamping is cut away on its upper side so that it may swing into the dotted 75 line position indicated at 48 in Fig. 2, the rivet 49 which secures the locking device to the stanchion also serving as a pivot about which such swinging movement is effected. When the bunk is to be swung up into vertical 80 position, the locking device 45 is lifted into the dotted line position so as to permit the upper lee rail to be moved into the desired position as shown in Fig. 1 after which the locking device 45 is released and falls 85 by gravity into the position shown in Fig. 2 thereby securing the bunk positively in vertical position. When the bunk is in the dotted line position, shown in Fig. 1, the locking device 45 drops into the dotted line 90 position 50 shown in Fig. 2.

I claim—

1. The combination of a bunk provided with a pair of lee rails the ends of the rear lee rail constituting pivotal supports around 100 the axes of which the bunk may be rotated from horizontal to vertical position or vice versa; pins rigidly secured in the ends of said lee rails and so transversely positioned in the said ends that when the bunk is horizontal, said pins have their axes vertical and projecting downwardly and a set of stationary sockets for receiving the ends of said lee rails, the said sockets each comprising an axially horizontal cylinder slotted as to 105 its upper side and having its end flanged over, the said flanged end being slotted to position the end of the lee rail, said pins being located within the flange of the said socket whereby the rail end is locked securely 110 in said sockets, against longitudinal movement.

2. The combination of a bunk provided with a pair of side rails, the ends of the rear side rail constituting pivotal supports 120 around the axis of which the bunk may be rotated from horizontal to vertical position or vice versa; pins rigidly secured in the ends of said rail and so transversely positioned in the said ends that when the bunk is horizontal, said pins have their axes vertical and projecting downwardly, and a set of stationary sockets for receiving the ends of 125 said side rails, the said sockets each comprising an axially horizontal cylinder slotted as 130

to its upper side and having its end flanged over, the said flanged end being slotted to position the end of the side rail, said pins being located within the flange of the said socket whereby the bunk is locked securely in said sockets, the diameter of the end of the side rail in said socket being considerably less than the internal diameter of the said socket thereby permitting rotation of said pins within the said sockets when the bunk is swung on its pivotal axis.

3. The combination of an upright, a bunk pivotally supported thereby and provided with a projecting male pivot member having its axis horizontal, a socket on said upright having an opening for receiving the end of

said pivot member, said opening having an upper entrance for admitting the end of said pivot member, and a side aperture communicating with said entrance, the bottom 20 of said aperture constituting a pivotal support for said pivot member, said pivot member having within said socket an outwardly projecting part normally projecting downwardly when the bunk is in horizontal or operative position for preventing withdrawal of said pivot from said socket horizontally, and also constituting means for preventing upward movement of said pivot member out of said entrance when the bunk is swung 30 into abnormal or vertical position.

DON CARLOS TRAVIS.
